UNITED STATES PATENT OFFICE.

ROBERT S. KLOPFENSTEIN, OF WICHITA, KANSAS, ASSIGNOR TO NATIONAL LOCK-IN-TANK COMPANY, OF WICHITA, KANSAS, A CORPORATION.

FLUID-CONTROL LOCK FOR TANKS.

1,376,283.

Specification of Letters Patent. Patented Apr. 26, 1921.

Application filed July 19, 1918. Serial No. 245,790.

To all whom it may concern:

Be it known that I, ROBERT S. KLOPFENSTEIN, a citizen of the United States, residing at Wichita, in the county of Sedgwick 5 and State of Kansas, have invented new and useful Improvements in Fluid-Control Locks for Tanks, of which the following is a specification.

This invention relates to improvements in 10 fluid control locks for tanks, especially adapted for use in connection with the gasoline tanks of automobiles to cut off the supply of gasoline to the carburetor and thereby prevent an automobile from being used 15 by an unauthorized person.

One object of the invention is to combine 20 with a tank, a carburetor, and a connection between the tank and the carburetor, a valve to control the passage of fuel through the connection, a lock to operate the valve and a casing in which the lock is inclosed, said casing forming a part of said connection and causing the connection to be destroyed in the event that the lock is tampered with.

25 Another object of the invention is to provide an improved fluid control lock of this class which can be readily installed in the bottom of a gasoline tank.

Another object of the invention is to provide 30 an improved lock operated fuel control valve embodying a movable valve element and a block in which said valve element is arranged, said block forming a part of the fuel connection and being provided with a tortuous passage which prevents the valve element from being operated by any agency other than the lock.

Another object of the invention is to provide 40 an improved lock operated fuel control valve embodying a movable valve element and a block in which said valve element is arranged, said block forming a part of the fuel connection between the tank and the carburetor and being adapted to be arranged in the bottom of the tank and having an intake which is spaced above the bottom of the tank so that the valve is prevented from being choked with sediment.

With the above and other objects in view, 50 the invention consists in the construction, combination and arrangement of devices hereinafter described and claimed.

In the accompanying drawings:

Figure 1 is a vertical sectional view of a 55 lock operated fuel control valve embodying my invention and showing the casing in

which the same is installed as an auxiliary tank which forms a part of the fuel connection and which is attached to the tank of a vacuum feed apparatus.

Fig. 2 is a detail sectional view of the same, on a larger scale, and on a plane at right angles to that of Fig. 1.

Fig. 3 is a detail plan of the block and the needle valve or movable valve element.

Fig. 4 is an inverted plan of the lock mechanism which operates said needle valve.

Fig. 5 is a plan of the auxiliary tank and with the cover thereof removed.

Fig. 6 is an elevation of a modified embodiment of my invention in which the auxiliary tank is arranged directly as a part of the fuel connection between the gasoline tank and the carburetor.

The block 1, in which the fuel control needle valve 2 is arranged for operation, and to which the operating lock 3 is connected, is compact and substantially of cylindrical form and is adapted to be readily 80 installed in the bottom of a tank, it being necessary only to provide a comparatively small opening in the top of the tank and to enlarge the usual opening in the bottom of the tank sufficiently to receive the cylindrical plug 4 with which the block is provided, said plug being threaded to receive a nut 5. The block has a cylindrical upper portion 6 to receive a lock 7 which is here shown as a tumbler lock, such as a Yale lock 90

of well known construction and embodying a revoluble element 8 which can only be turned by means of a key which has been especially constructed for engagement by the various tumblers, the tumbler serving 95 to lock said element against rotation excepting when they are arranged in released position by the insertion of the key. The block is also provided with a chamber 9 directly below the lock and the revoluble lock element 8 is provided with a tappet stud 10 attached eccentrically thereto and which extends down into said chamber 9. The block is also formed with enlargements 11, 12 on opposite sides and with a flange 13 to bear 105 above the bottom of the tank. An inlet opening 14 leads from one side of the block to the chamber 9 and is spaced above the bottom of the tank as shown. A vertical bore 15 is made partly through the stud 4 110 from the bottom thereof and has a threaded counterbore 16 at its lower end in which one

end of the fuel supply pipe 17, which leads to the carbureter, is screwed. A conical valve seat 18 is provided for the pointed end of the needle valve and an inclined bore 19 leads from said valve seat to the bore 15. Said bores 15, 19 form a tortuous pass through which the gasolene or other fuel can freely flow when the valve is in open position but said tortuous pass effectually 5 prevents the valve from being opened by an instrument other than the lock, as a wire or the like which might be inserted upwardly through the bore 15 by a person who attempts to tamper with the lock and who has 10 disconnected the pipe 17 would be bent in the tortuous pass and rendered incapable of moving the valve 2 to open position. The valve element 2 has a stem 20 and has a head 21 at the outer end of said stem. The 15 head operates in a recess 22 in the enlargement 11 of the block and a spring 23 is also arranged in said recess and exerts its tension against the head to normally hold the needle valve or movable valve member 2 in firmly 20 closed position and so that it can be only moved to open position by operating the lock by means of the appropriate and especially constructed key.

Such a key is indicated at 24 and the 25 shank of the key is foldable and comprises members 25, 26, 27 which are pivotally connected together as at 28, 29. The outer member 27 has a handle 30 which projects from one side thereof. A tube 31 is attached 30 to the top of the lock and extends therefrom to the top of the tank. The key is arranged in the tube, the latter serving to prevent the key from bending at the joints and to maintain the key in the required position. The upper end of the tube has a 35 segmental recess 32 in which the handle of the key operates, the ends of said recess serving to limit the movement of the key.

In the form of the invention shown in 40 Fig. 1 the tank in which the lock operated fuel control valve is installed is an auxiliary tank 33 which forms a part of the connection between the gasolene tank and the carbureter and the said auxiliary tank 45 is arranged at one side of the tank 34 of the vacuum feed apparatus, of well known construction. The auxiliary tank is connected to the tank 34 by a nipple 35 which passes through the contiguous side walls of 50 said tanks and has a head 36 which bears against the inner side of the wall of the tank 33 and is threaded on that end which projects into the tank 34. A ring 37, of hardened metal, which cannot be readily 55 cut or sawed, is arranged around the nipple and between the walls of the tanks, 33, 34 and on the threaded inner end of the nipple is screwed a nut 38 which is also secured by means of a cotter pin 39 which passes 60 through alining openings in the nipple and 65

nut and which can be arranged in place only when the top of the tank 34 has been removed. The upper end of the auxiliary tank is connected to the top of the tank 34 by a band 40 which passes around the tank 70 33 and the ends of which are secured on the top of the tank 34 by screws or other suitable devices 41. It will be understood that the tank 33 cannot be disconnected from the tank 34 excepting by first removing the top of the tank 34 and this, owing to the connections with said tank 34, could not be done without so disabling the apparatus as to prevent the operation of the car. A cover 42 is provided for the auxiliary tank, which is pivoted thereon as at 43, and, in practice, a suitable lock may be also provided for this cover. The said cover serves to cover and conceal the handle of the key when the latter is arranged in place in the lock. It will be understood that the needle valve can only be moved to open position by the operating lever through the instrumentality of its key and that the needle valve is held in open position, against the tension of the spring 23 when the tappet 10 is at the dead center. Before the key can be removed from the lock the cylinder of the lock must be turned 85 a sufficient distance to cause the tappet 90 member 10 to release the head of the needle valve and thereupon the spring acts to close the needle valve and to hold the same in closed position.

In Fig. 6 of the drawing I show another 100 arrangement of my invention in which the vacuum feed apparatus is omitted and the auxiliary tank 33 is connected directly to the gasolene tank 44 by a pipe 45. A pipe 17^a leads directly to the carbureter 46 from 105 the stud of the block which is secured in the bottom of the auxiliary tank.

Other modifications may be made within the scope of my invention and changes may be made in the form, construction and arrangement of the several parts, within the 110 scope of the appended claim.

Having thus described my invention, I claim:

In a fluid control lock, the combination 115 of a tank having an inlet and an outlet for fluid, a rectilinearly movable, spring-pressed valve for controlling a passage in the tank intermediate said inlet and outlet, a lock in the tank and embodying a rev- 120 oluble element actuatable by a key and provided with a tappet stud eccentrically disposed to coöperate with the valve, a tube extending outwardly from the lock to a wall of the tank; said tube being adapted 125 for the manipulation therein of the key complementary to the lock.

In testimony whereof I affix my signature.

ROBERT S. KLOPFENSTEIN.
